UNITED STATES PATENT OFFICE.

JULIUS EDGAR LILIENFELD, OF LEIPZIG, GERMANY.

ROENTGEN-RAY TUBE.

1,218,423.

Specification of Letters Patent.

Patented Mar. 6, 1917.

Application filed April 17, 1914, Serial No. 832,606. Renewed July 25, 1916. Serial No. 111,279.

To all whom it may concern:

Be it known that I, JULIUS EDGAR LILIENFELD, subject of the Austro-Hungarian Emperor, residing at Leipzig, Germany, have 5 invented certain new and useful Improvements in Roentgen-Ray Tubes; and I do hereby declare the following to be a full, clear, and exact description of the invention, such as will enable others skilled in 10 the art to which it appertains to make and use the same, reference being had to the accompanying drawings, and to letters or figures of reference marked thereon, which form a part of this specification.

15 This invention relates to the production of Roentgen rays and has special reference to an apparatus designed to give high efficiency in the production of rays of this character. In order to obtain a constant working of the tube in the production of such rays a high degree of vacuum in the tube is essential. As pointed out in my companion application filed October 2, 1912, Serial No. 723,583, it is advisable to produce 20 such a vacuum that no discharge will take place, under ordinary conditions, between the electrodes of the tube, the gas pressure being reduced to such a limit that conductivity in the space must be attained by 25 means independent of the means for producing the discharge which effects the production of the Roentgen rays before such discharge can take place.

30 As further pointed out in the above application, this conductivity is produced by means of an electrode heated to incandescence and which is preferably termed a glower electrode. In order to more efficiently and economically produce a tube of 35 this description and to effect the production of Roentgen rays, it is necessary that the electrostatic field from the glower electrode or cathode to its anode shall not interfere with the starting of the electrostatic field between the cathode and anticathode used for the production of rays.

This is of importance, as, for instance, when the production of extremely hard rays such as are used for therapeutic purposes is 50 desired, because of the use of extremely high tensions, which would disadvantageously affect the working of the glower discharge if the latter was not electrostatically screened from their influence. On the other hand, if it be supposed that the glower discharge is absolutely electrostatically

screened from the high tension field between the cathode and anticathode there arises the advantage that the glower electrode may be positioned in any desired place without reference to the position of the remaining electrodes, and this without the discharge producing the rays exerting a bad influence on or extinction of the discharge from the glower.

60 The principal objects of the present invention are therefore to provide a tube wherein there can be no interference between the electrostatic field from the glower cathode and its anode and the electrostatic field employed for production of rays even at the highest tensions. Second, that the field production between the cathode and anticathode shall not only not inhibit, but even assist in the production of a field 70 between the cathode and anode used for the production of the rays.

65 With the above and other objects in view the invention consists in general of certain novel details of construction and combination of parts hereinafter fully described, 75 illustrated in the accompanying drawings, and specifically claimed.

In the accompanying drawings, like characters of reference indicate like parts in 80 the several views, and:

Figure 1 is a section through one form 85 of tube constructed in accordance with this invention.

Fig. 2 is a section through a second form 90 of tube constructed in accordance with this invention.

In the form shown in Fig. 1, herein, there is employed a tube having the bulbs 10 and 11 which are connected by a neck 12, the 95 part of the neck adjacent the bulb 10 being enlarged as at 13. Within the enlarged portion 13 the glass of the tube is extended to form a hollow cylindrical projection 14, the end of which supports the combined 100 anode and cathode which consists of a suitable plate 15 curved to present a concave side of the bulb 10 and having adjacent its periphery a flange 16 which surrounds the end of the projection 14. Moreover the plate 105 15 is provided with perforations 17, one of which is preferably centrally located. Furthermore, within the bulb 10 is mounted the anti-cathode 18 preferably provided with a shield 19. In the bulb 11 is a large 110 loop of wire arranged as a glower cathode. This loop may extend as far from the main

axis of the Roentgen electrodes as it is suitable to obtain the necessary glower surface for the purpose of working the tube with heavy currents (snap shots) 20 having suitable wiring connections 21 extending out of the bulb. Within the neck is located the anode 20' for the glower cathode 20. This anode may, if desired, be omitted so that the electrode 15 may act as a combined anode to the glower and cathode to the anticathode 18.

In the form shown in Fig. 2 the tube is provided with a pair of bulbs 22 and 23. These bulbs are connected by a neck 24 and extending upward in this neck is a hollow cylindrical projection 25 formed from the glass and spaced at its upper end from the walls of said neck. This glass projection is surrounded by a metallic cylinder 26 where to is connected the combined cathode and anode 27 having a centrally disposed opening 28. Furthermore, within the cylindrical extension 25 is a second hollow cylindrical member 29 which is held spaced from the first member by metallic screening members 30. The purpose of these electrostatically screening members is to prevent the discharge passing between the members 29 and 25 so that any discharge, in order to pass through the member 25, must also pass through the member 29; therefore the discharge is held within the inner member 29.

The upper end of the bulb 22 is provided with an inward tubular extension 31 which has fused in its inner end a metallic sleeve 32 carrying a second sleeve 33 which is closed at its inner end and supports the diagonally disposed anticathode 34. In the bulb 23 is provided a glower cathode 35 which may be heated through the usual wires 36. It will be noted that this glower cathode may have any desired position in reference to the axis of the tube without affecting the operation since it is electrostatically screened from the high tension field between the cathode and anticathode.

Each of these forms is provided with suitable wiring connections as indicated in general at 37.

It is to be noted that in each form thus described the discharge from the glower cathode will pass to the back of the combined cathode and anode and that by the impact of this discharge on the combined anode and cathode there is produced a condition suitable to start a discharge from the Roentgen cathode, the flow of the charged particles being in the same direction as the flow from the cathodic side of the combined anode and cathode.

Having thus described the invention, what is claimed as new, is:—

1. In a Roentgen ray tube, the combination of a high vacuum tube, with a cathode and its anticathode, and a third electrode

electrostatically screened from the anticathode by means independent of the tube walls and possessing the property of producing a discharge in a high vacuum, the first mentioned cathode being arranged between the 70 anticathode and the third electrode.

2. In a Roentgen ray tube, the combination of a high vacuum tube, with a cathode and its anticathode, and a third electrode electrostatically screened from the anticathode and possessing the property of producing a discharge in a high vacuum, the first mentioned cathode being arranged between the anticathode and third electrode 75 and serving as a screen between the third electrode 80 and the anticathode.

3. In a Roentgen ray tube, the combination of a high vacuum tube, with a cathode and its anticathode, and a glower cathode electrostatically screened from the anticathode 85 and possessing the property of producing a discharge in a high vacuum, the first mentioned cathode being arranged between the anticathode and the glower cathode.

4. A Roentgen ray tube provided with a 90 cathode, an anticathode, and a third electrode between the cathode and anticathode consisting of a disk and having a perforation therein.

5. A Roentgen ray tube provided with a 95 glower cathode, an anticathode, and a third electrode constituting a combined anode and cathode located between the first and second electrodes and having a perforation therein.

6. A Roentgen ray tube provided with a 100 glower cathode, an anticathode, and a third electrode between the first two, said third electrode constituting the anode for the glower cathode and the cathode for the anticathode and being perforated as and for the 105 purposes set forth.

7. A Roentgen ray tube provided with a glower cathode, an anti-cathode, and a third electrode between the first two, said third electrode constituting the anode for the 110 glower cathode and the cathode for the anti-cathode and being perforated to receive impact of the discharge from the glower cathode, said tube being further arranged to concentrate the discharge of the glower on said 115 perforated part of the third electrode.

8. A Roentgen ray tube including a pair of bulbs united by a neck and having a high vacuum, a septum across said neck and provided with a perforation, said septum constituting a combined cathode and anode, and an electrode in each bulb.

9. A Roentgen ray tube including a pair of bulbs united by a neck and having a high 125 vacuum, a septum across said neck and provided with a perforation, said septum constituting a combined cathode and anode, an electrode in each bulb, and means within the neck to concentrate discharge to the perforation.

10. A Roentgen ray tube including a pair of bulbs united by a neck and having a high vacuum, a tubular projection extending from one end of said neck toward the other end thereof, a metallic sleeve on the free end of the tube, said sleeve carrying at its end a perforated diaphragm constituting an anode and cathode combined, a tube mounted within the projection and spaced from the walls thereof, metallic screens between the inner and outer tubes, a glower cathode which is located in the bulb at the base of the tubular projection, and an anticathode in the remaining bulb.
15. 11. A Roentgen ray tube including a pair of bulbs united by a neck and having a high vacuum, a tubular projection extending from one end of said neck toward the other end

thereof, a metallic sleeve on the free end of the tube, said sleeve carrying at its end a perforated diaphragm constituting an anode and cathode combined, a tube mounted within the projection and spaced from the walls thereof and grounded to the said metallic sleeve, metallic screens between the inner and outer tubes, a glower cathode which is located in the bulb at base of the tubular projection, and an anticathode in the remaining bulb.

In testimony whereof I have signed my name to this specification in the presence of two subscribing witnesses.

JULIUS EDGAR LILIENFELD.
